UNITED STATES PATENT OFFICE.

CHARLES PFANNENSTIEHL, OF NEW YORK, N. Y.

BOTTLE-CORKING MACHINE.

SPECIFICATION forming part of Letters Patent No. 274,221, dated March 10, 1883.

Application filed June 7, 1882. (No model.)

To all whom it may concern:

Be it known that I, CHARLES PFANNENSTIEHL, of the city of New York, county and State of New York, have invented a new and 5 Improved Machine for Corking Bottles, of which the following specification is a full, clear, and exact description.

This invention relates to a new machine for corking bottles, and is adapted more particularly to cork bottles under my Letters Patent 10 No. 171,315 of December 21, 1875.

The invention consists, principally, in the combination, in a corking-machine, of a plunger with a revolving feed-block having chambers for reception of corks, and with a tube for charging said chambers; also, in the mechanism for feeding the corks, revolving the feed-block, and in other details of construction hereinafter more fully pointed out.

20 In the accompanying sheets of drawings, Figure 1, Sheet 1, is a front elevation of my new corking-machine. Fig. 2, Sheet 1, is a vertical transverse section on line x x , Fig. 1. Fig. 3, Sheet 2, is a horizontal section on line y y , Fig. 2. Fig. 4, Sheet 2, a similar section on line z z , Fig. 2; and Fig. 5, Sheet 2, a vertical central section on line w w , Fig. 4. Fig. 6, Sheet 3, is a perspective view of the mechanism which charges the feed-tube. Figs. 3, 25 4, 5, and 6 are on a larger scale than the other figures.

Similar letters of reference indicate corresponding parts in all the figures.

The letter A represents the frame of my corking-machine, into the upper portion of which is hung a shaft, a , to which rotary motion may be imparted by hand or steam. The shaft a has a crank, b , to which is pivoted a rod, c , the lower end of which is connected to a plunger, 35 40 d . By revolving the shaft a , up and down motion is imparted to the plunger d .

e is a horizontal feed-block, having six (more or less) chambers open at top and bottom for reception of corks, and charged as hereinafter described. This feed-block is revolved around 45 its center intermittently, and is so arranged in relation to the plunger that one of its chambers, charged with a cork, is beneath the plunger when the latter descends. Beneath the 50 feed-block e is a plate, f , having an aperture directly below the plunger, and closing at the bottom the chambers of the feed-block not in

line with the plunger. The plunger pushes the cork beneath it out of feed-block e , through aperture in plate f , into a fixed nozzle, g , from whence it enters the neck of a bottle, B , placed beneath nozzle g , upon a platform, h . This platform is provided with washers i i , to vary its height to correspond to the height of different bottles. It is, moreover, by rods j j , connected to shaft a by eccentrics or cranks k k , placed in opposite direction to crank b . In this way, when the plunger d descends, the platform h is raised against the nozzle g , and the bottle B is tightly held in place, while it 60 is released when the plunger ascends. Intermittent rotary motion is imparted to the feed-block e by a rod, l , passing loosely through its center, and provided with a pawl, m , engaging into the teeth of a ratchet-wheel, n , which is 65 rigidly secured to the face of the feed-block. Near the upper end the rod l is provided with a pin, o , bearing upon the upper side of a projection, p , on the cross-head q of plunger d . The bearing-surface of projection p has an inclined bevel, so as to turn the rod l whenever 70 it ascends a sufficient distance to revolve feed-block e and bring the next charged chamber in line vertically with the plunger d . As soon as projection p is raised above pin o and releases the same the rod l is swung back into its former position by a spring, v , Fig. 3. This motion of rod l will not be communicated to feed-block e , as the pawl, on its backward motion, does not engage the teeth of the ratchet-wheel n , and thus the feed-block is only 75 revolved in one direction. (Indicated by arrows in Fig. 4.)

The charging of the chambers of the feed-block is effected as follows: Above the feed-block, and diametrically opposite the plunger, is a tube, r , into which the corks are dropped from a hopper, s . This tube is of such a diameter that corks can only enter and remain in it in an upright position. Between the upper end of the tube r and the lower end of the hopper is a vessel, t , terminating in a nozzle, which enters the mouth of tube r . The nozzle is also of such a diameter near its lower end that corks can enter it only in an upright position. The vessel t is slightly inclined, and is loosely hung to the hopper by springs, or in an equivalent manner. It receives a rapid vibratory motion by the mechanism illustrated 80 85 90 95 100

in Fig. 6. This mechanism is as follows: To an arm, a' , projecting from frame Δ , is pivoted a ratchet-wheel, u , which is revolved by a belt driven by driving-shaft a . Through the arm a' , and through a sleeve, b' , which it supports, passes loosely the shank d' of a pawl, e' . The lower end of this shank is rigidly attached to vessel t . The pawl e' engages the teeth of the ratchet-wheel u , and is held against them by a spring. When the ratchet-wheel u is revolved, the pawl e' is caused to vibrate, and such vibration is imparted through shank d' to vessel t .

The operation of the machine is as follows: 15 Corks are dropped gradually into the hopper and fall upon the vessel t . The vibratory motion of this vessel will cause those corks which are in a proper upright position to enter its nozzle and drop into tube r . The corks will 20 accumulate in said tube and fill the same, as well as the nozzle of vessel t . As the feed-block e revolves, the chambers passing under the end of tube r are successively charged with the then lowermost cork. Whenever one cork 25 is received by the feed-block, the column of corks in tube r drops, and room is made in the upper end of the nozzle to receive a new cork. The charged chambers of the feed-block pass one after the other under the plunger, and are 30 forced into the neck of the bottle.

I claim as my invention—

1. The combination, in a corking-machine, of a plunger, revolving feed-block having chambers for reception of the corks, and a tube for 35 charging the chambers of the feed-block, substantially as herein specified.

2. The combination, in a corking-machine, of a plunger, a feed-block receiving intermittent rotary motion, and a charging mechanism, with an adjustable platform, h , beneath the plunger 40 for the reception of a bottle, substantially as specified.

3. The combination, in a corking-machine, of hopper s , vessel t , to which reciprocating motion may be imparted, and feed-tube r , with 45 feed-block e and plunger d , substantially as specified.

4. The combination, in a corking-machine, of the crank-shaft a , rod c , and plunger d with the feed-block e and plate f , and with mechanism for revolving and charging the feed-block, substantially as specified.

5. In a corking-machine, the mechanism for imparting intermittent rotary motion to the feed-block e , consisting of rod l , having pawl- and-ratchet connection with feed-block, and a pin, o , bearing upon projection p of the plunger, all being so arranged that the feed-block is revolved during the ascent of the plunger, substantially as specified. 55

6. The combination, in a corking-machine, of crank-shaft a with rod c , plunger d , revolving feed-block e , charging mechanism s t r , platform h , and rods j j , substantially as and for the purpose specified. 60

CHARLES PFANNENSTIEHL.
